FOLDING MACHINE

John Mentges, Sidney, Ohio

Application May 29, 1931. Serial No. 541,053

76 Claims. (Cl. 270—62)

This invention relates to folding machines, and more particularly to folding machines of the type employed in the folding of sheets of paper or the like.

5 In the patent to W. O. Blake, No. 1,655,491, granted January 10, 1928, there is disclosed paper folding machinery including a loop folder and a knife folder and wherein the knife operates through the loop folder grid to tuck a sheet delivered therein into folding rollers mounted at the side of the grid opposite that on which the knife is mounted. One object of the present invention is to provide a folding machine of the type just referred to, which embodies improvements 15 in the manner of handling and delivering the sheets, and enables the knife, through the medium of novel means, to be thrown out of operation when the loop folder is employed to fold the sheets.

20 Another object of the present invention is to provide improvements in folding machines, which may be utilized in connection with loop folders, or knife folders, or combinations thereof, and result in increased efficiency of the folding means embodying said improvements.

Another object of the present invention is to provide a folding machine which embodies a folding knife and novel means for controlling the operation of said knife in accordance with the 25 character of the folded product of said machine.

Another object of the present invention is to provide a folding machine which embodies feed or drive-up rollers movable to operative and inoperative positions and controlling the operation 30 of a folding knife.

Another object of the present invention is to provide a folding machine which enables sheets to be fed longitudinally and laterally in a grid for registration with a folding knife movable 35 therethrough to fold said sheets.

Another object of the present invention is to provide a folding machine which embodies a grid having means for moving a sheet laterally thereof to register it properly with the sheet folding 40 means.

Another object of the present invention is to provide a folding machine which embodies a grid having a sheet registering device movable laterally thereof and adjustable to act on sheets of 45 various sizes.

Another object of the present invention is to provide a folding machine which embodies a grid having sheet stops at one end and one side thereof to limit movement of sheets both longitudinally and laterally of the grid.

Another object of the present invention is to provide a folding machine which embodies a grid having a sheet stop adjustable laterally thereof to various operative positions.

Another object of the present invention is to 60 provide a folding machine which has roller adjusting devices and novel means for locking the same against accidental displacement.

Another object of the present invention is to 65 provide a folding machine which has a reversible grid and deflector constructed for association with sheet feeding and folding rollers so that in one position of the grid the rollers may fold a sheet and in a reverse position of the grid the sheet may be passed through said rollers without 70 folding.

Another object of the present invention is to provide a folding machine which has novel stacking means arranged to swing into operative relation with one or the other of a plurality of folding 75 devices.

Another object of the present invention is to provide a folding machine which has novel stacker operating means.

Another object of the present invention is to 80 provide a folding machine which has novel means for swinging a stacker to, and locking the same in, different operative positions.

These and other objects of the present invention will appear as the following description there- 85 of proceeds, and in order to more clearly understand said invention, reference may be had to the accompanying drawings which illustrate one embodiment of the inventive idea.

In said drawings: 90

Fig. 1 is a side elevation of a folding machine equipped with devices embodying the present invention;

Fig. 2 is a vertical longitudinal sectional view 95 on the line 2—2 of Fig. 4;

Fig. 3 is an enlarged side elevation, partly in section, of a folding knife and mechanism for operating the same;

Fig. 3a is a detail perspective view of a grid, stop devices, and scales employed in conjunction 100 with said stop devices;

Fig. 4 is a transverse vertical sectional view on the line 4—4 of Fig. 1;

Fig. 5 is a detail perspective view of roller adjusting means and locking means therefor, the parts being shown separated for purposes of clearer illustration;

Fig. 5a is an enlarged detail sectional view of 105 portions of the roller adjusting means and locking means therefor shown in Fig. 5;

- Fig. 5b is a view similar to Fig. 5a, showing other roller adjusting means and locking means therefor, embodying the present invention;
- Fig. 6 is an enlarged side elevation of stacker 5 operating mechanism shown in Figs. 1 and 2;
- Fig. 6a is a detail sectional view of a reversible grid and deflector shown in Fig. 4;
- Fig. 7 is an enlarged detail perspective view of sheet stackers and operating mechanisms therefor shown in Figs. 1, 2, 4 and 6; and
- Fig. 8 is an enlarged detail perspective view of a grid and a knife movable therethrough, showing means for controlling the operation of the knife and means for moving sheets laterally of the grid to register them with respect to said knife.
- Referring to the drawings, wherein like reference characters designate like parts throughout the several views, 5 indicates broadly a support or stand the sides 6 and 7 of which are connected together by cross members (not shown) secured thereto in any suitable manner. This support or stand has secured thereto, as by bolts 8, 8 and 9, 9, the two sides 10 and 11, respectively, of a frame which is indicated broadly at 12 and 20 carries the various movable parts of a folding machine and associated devices embodying the present invention (Figs. 1, 2 and 4). The sides 10 and 11 of the frame 12 are connected together by cross members 13, 13', 14, 14', and 15 which 25 are bolted or otherwise suitably secured to said sides, as at 16, 16', 17, 17', and 18, respectively. The sides 10 and 11 of frame 12 are provided with feet 18' having suitable openings therein for the bolts 8, 8 and 9, 9.
- The movable parts on the frame 12 may be 30 driven from any suitable source of power, herein shown as an electric motor 19 supplied with current from any suitable source and controlled by any suitable type of switch (not shown) for starting and stopping said motor. Fixed on the armature shaft 20 of the motor 19 is a pulley 21 around which passes a belt 22 that also passes around a pulley 23 which is fixed on a shaft 24 extending transversely of the machine and journalled in suitable bearings on the sides 10 and 11 of frame 12. This shaft 24 constitutes the main 35 drive shaft of the machine from which the various movable parts thereof are driven as hereinafter described.
- The motor 19 is bolted or otherwise suitably secured, as at 25, on a plate 26 which, in turn, is bolted or otherwise suitably secured, as at 27, on one arm 28 of an L-shaped bracket 29 which is pivoted, as at 30, on the side 7 of the support or stand 5. The other arm 31 of the bracket 29 has an enlarged upper end 32 provided therein with an arcuate shaped slot 33 through which extends a bolt 34 that also extends through a suitable opening in one of the feet 18' on the side 11 of frame 12 and is secured against displacement therefrom by any suitable means for this purpose. By loosening the bolt 34, the bracket 29 and the motor 19 thereon may be swung about the pivot 30 thus enabling the tension of belt 22 to be regulated as desired. When the proper or desired tension on belt 22 is obtained, the bolt 34 is tightened to hold the bracket 29 and the motor 19 against accidental swinging movement about the pivot 30.
- The support or stand 5 may, if desired, be dispensed with, and the folding machine instead of being mounted on said stand, could be placed on any other suitable support such as a table or the like. In this case the bolts 8, 8 and 9, 9 would be removed and the frame 12 and parts carried thereby placed on said table with the feet 18' resting thereon and, if desired, secured thereto by said bolts or other suitable fastening means. The bracket 29 and the motor 19 could in this instance, be secured to the table, or the bracket could be dispensed with and the motor mounted on the floor or other suitable supporting means. The motor would, of course, be connected with the shaft 24, as before described, or by any suitable driving connections for said motor with said shaft.
- The sheets to be folded by the machine may be fed thereto from any suitable source of supply, either by hand, or by any suitable automatic feeder. As herein shown, the sheets are fed by hand into the machine from a supply carried by a pack holder which is indicated broadly at 35 and has opposite side members 36 pivoted at 37 on the sides 10 and 11 of frame 12 at the top thereof. The side members 36 of pack holder 35 are connected together by cross members 38 bolted or otherwise suitably secured to said side members and extending transversely thereof. Slidably mounted on the cross members 38 are brackets 39 on which are bolted or otherwise suitably secured the side guides 40 of the pack holder. Brackets 39 are releasably secured on the cross members 38 by thumb screws 41 or other suitable means for this purpose.
- The pack or supply of sheets is supported between the side guides 40 on a series of juxtaposed slats 42 or similar elements having spring clips 43 which are engaged over the cross members 38 and serve to removably secure said slats in position thereon. The width of the pack holder 35 may be increased or decreased, as desired, to accommodate sheets of various sizes, by moving the brackets 39 and the side guides 40 along the cross members 38 and increasing or decreasing the number of slats 42 between said side guides. The clips 43 on the slats 42 enable them to be readily secured to and removed from the cross members 38, and through the medium of the thumb screws 41, the brackets 39 and the side guides 40 may be secured in any desired position of adjustment on said cross members.
- In the normal operation of the machine, the pack holder 35 is positioned as shown in full lines in the drawings and the sheets are fed one at a time from the supply thereof on said pack holder past sheet feeding and control mechanism which is indicated broadly at 44 (Fig. 2) and serves to feed and control the delivery of sheets to the first folding mechanism indicated broadly at 45. A second folding mechanism indicated broadly at 46 is disposed below the pack holder 35 and a third folding mechanism, indicated broadly at 47, is disposed directly below said second folding mechanism. In order to have ready access to the folding mechanism below the pack holder 35, the latter may be swung up from its operative position indicated in full lines in Fig. 2, to an inoperative position indicated in dotted lines in said figure.
- The pack holder may be held up in its inoperative position by any suitable means for this purpose herein shown as a support 48 having one end thereof pivotally connected at 49 with one of the side members 36 of the pack holder. The opposite end of the support 48 is provided thereon with a hook 50 which, when the pack holder is raised to its inoperative position, engages over one of a pair of bolts 51 carrying nuts 52 on which the side members 36 of said pack holder normally rest. The bolts 51 extend through suitable openings in the sides 10 and 11 of frame 12

at the top thereof, and by disengaging the hook 50 from the adjacent bolt 51, the pack holder may be dropped down to its normal operative position where the support 48 depends downwardly from 5 said pack holder exteriorly of the frame 12.

The sheet feeding and control mechanism 44 includes feed rollers 53, a drop roller 54, preferably made of rubber or other frictional material, and a control finger 55. These devices are operated by mechanism hereinafter described so that during each cycle of operation of the machine, the drop roller 54 and the finger 55 are raised, the latter momentarily stopping the incoming sheet, whereupon said finger and the drop roller 15 are lowered to move the finger out of the normal path of travel of the sheet and enable the drop roller to engage the sheet with one of the feed rollers 53 which then act to feed the sheet between knurled feed rollers 56 and 57 of the folding mechanism 45. The knurled rollers 56 and 57, together with a knurled roller 58, a grid 59, and a stop 60 in said grid, constitute the main elements of one of a pair of of loop folding devices comprising the folding mechanism 45. The other 25 of said loop folding devices includes knurled rollers 61, 62, 63, a grid 64, and stops 65 in said grid.

The roller 56 extends transversely of the frame 12 and has trunnions 56' (Fig. 1) journalled in fixed bearings 66 on the sides 10 and 11 of said 30 frame. The rollers 57 and 58 also extend transversely of the frame 12, in parallel relation with each other and the roller 56, and have trunnions 57', 58' journalled in blocks 67 slidably mounted in guides 68 on said sides 10 and 11 of the frame 35 12. The roller 61 extends transversely of the frame 12 and has trunnions 61' journalled in fixed bearings 69 on the sides 10 and 11 of said frame. The rollers 62 and 63 also extend transversely of the frame 12, in parallel relation with the roller 40 61, and have trunnions 62' and 63' journalled in blocks 70 slidably mounted in guides 71 on said sides 10 and 11 of the frame 12. The various rollers of the folding mechanism 45 are driven continuously in the directions of the arrows (Fig. 45 2) through driving connections for said rollers with the shaft 24 that are preferably comprised by the following devices.

Fixed on the main drive shaft 24 is a spur gear 72 which meshes with a similar gear 73 that is 50 fixed on a stub shaft 74 journalled in a suitable bearing on the side 11 of frame 12 (Figs. 1 and 2). The stub shaft 74 also has fixed thereon a spur gear 75 which meshes with a similar gear 76 fixed on one of the trunnions 61' of the roller 61. The 55 roller 61 is thus driven continuously by the described driving connections therefor with the continuously driven shaft 24, and said roller serves to continuously drive the rollers 62 and 63 through the medium of a spur pinion 77 (Fig. 2) which is 60 fixed on the trunnion 61' that carries the gear 76 and meshes with similar pinions 78 and 79 fixed on corresponding trunnions 62' and 63', respectively, of the rollers 62 and 63.

The roller 56 is driven continuously by the spur gear 76 which, for this purpose, meshes with a similar gear 80 fixed on one of the trunnions 56' of said roller. The roller 56, in turn, serves to continuously drive the rollers 57 and 58 which, for this purpose, have fixed on corresponding trunnions 57' and 58' thereof, spur pinions 81 and 82, respectively, which mesh with a similar pinion 83 fixed on the trunnion 56' that carries the spur gear 80.

The feed rollers 53 are continuously driven 75 from the roller 56 in the direction indicated by

the arrow (Fig. 2), and for this purpose the spur pinion 83 meshes with an idler pinion 82' journalled in any suitable manner on the side 11 of frame 12 and, in turn, meshing with a spur pinion 83' fixed on a shaft 84 which carries the 80 feed rollers 53. This shaft 84 extends transversely of the frame 12, and is journalled in suitable bearings on the sides 10 and 11 thereof. The feed rollers 53 and the finger 55 are arranged for movement in suitable openings formed in a plate 85 over which the sheets are fed from the pack holder 35 to the rollers 56 and 57. This plate 85 extends transversely of the machine across the entire width thereof and is bolted or otherwise suitably secured on the sides 10 and 11 of frame 12 at the top thereof.

The drop roller 54 and the finger 55 are preferably operated and mounted as follows. Fixed on the main drive shaft 24 is a spur pinion 86 (Fig. 1) which meshes with a large spur gear 87 fixed on a main cam shaft 88 extending transversely of the frame 12 and journalled in suitable bearings on the sides 10 and 11 thereof. The cam shaft 88 is thus driven continuously from the shaft 24 through the described driving connections therebetween. Fixed on the cam shaft 88 to rotate continuously therewith, is a cam 89 engaged by a roller 90 journalled on an arm 91 pivoted at 92 on the side 10 of frame 12. This arm 91 has pivotally connected therewith, as at 93, one end of a link 94 the opposite bent end of which is pivotally connected, as at 95, with an arm 96 fixed on a shaft 97 at one end thereof. This shaft 97 extends transversely of the frame 12 across its entire width, and is journalled in suitable bearings on the sides 10 and 11 thereof. The shaft 97 has fixed thereon arms 98 that carry a rotatable shaft 99 on which the drop roller 54 is mounted.

Pivotedly connected at 95 with the link 94 is one end of a link 100 the opposite end of which is pivotally connected, as at 101, with the free end of an arm 102 that is fixed on a rockshaft 103. This rockshaft 103 has fixed thereon the finger 55, and said rockshaft extends transversely of the frame 12 and is journalled in suitable bearings on the sides 10 and 11 thereof. The arm 102 has connected therewith, as at 104, one end of a spring 105 the opposite end of which is connected, as at 106, with the side 10 of frame 12. This spring 105 tends to exert a downward pull on the drop roller 54, the finger 55, and the link 95, and continually maintains the roller 90 in engagement with the cam 89. The link 94 is thus cam-operated in one direction and spring-operated in the opposite direction, and said link, through the described connections therefor with the drop roller 54 and the finger 55, serves to raise and lower said roller and finger at predetermined intervals with the resulting action thereof on the sheets as previously described.

The folding mechanism 45, as previously pointed out, includes the rollers 56, 57, 58 and 61, 62, 63. The rollers 56 and 61 are journalled in fixed bearings, as before described, whereas the rollers 57, 58 and 62, 63 are journalled in movable bearings for adjustment and yielding action relative to the rollers 56 and 61, respectively. In accordance with the present invention, adjusting devices are provided for the yieldable rollers, which facilitate yielding action thereof and are provided with locking means so constructed and operated as to prevent accidental displacement of the adjusting devices after they have been actuated to properly adjust the rollers. Accordingly, the blocks 67 are 140 145 150

provided therein with suitable openings the walls of which are threaded to receive the threaded ends 107 of adjusting bolts 108 extending loosely through suitable openings in the sides 10 and 11 of frame 12 and having threaded ends 109 projecting outwardly therefrom (Figs. 1, 2, 5 and 5a). The adjusting bolts 108 have flattened portions 110 which extend adjacent the threaded ends 107 into the openings in the blocks 67. Screws 111, or the like, threaded in suitable openings in the blocks 67, engage the flattened portions 110 of adjusting bolts 108 and prevent the same from turning in said blocks. Mounted on the adjusting bolts 108 are springs 112 corresponding ends of which bear against the blocks 67. The opposite ends of the springs 112 bear against the walls 113 of enlarged openings 114 in which the blocks 67 are inserted for movement into the guides 68.

The springs 112 enable the rollers 57 and 58 to yield relative to the roller 56 in the feeding of sheets through said rollers, and the rollers 57 and 58 are adjusted with respect to the roller 56, by adjusting nuts 115 which are threaded on the ends 109 of bolts 108 and bear against the sides 10 and 11 of frame 12. The rollers 57 and 58 may be adjusted relatively to the roller 56 by turning the nuts 115 to move the bolts 108, blocks 107, and rollers 57, 58, and after the desired adjustments of said rollers have been obtained, the adjusting nuts 115 are locked by thumb screws 116 threaded through suitable openings in heads 117 secured, as by screws 118, on the threaded ends 109 of the bolts 108. Each of the thumb screws 116 is provided with an enlarged upper end 116' adapted to bear against the head 117, and a smooth reduced lower end 118' adapted to engage in one of an annular series of openings 119 (Figs. 5 and 5a) formed in the nut 115. The linear dimensions of the openings 119, the screws 116 and the lower smooth reduced ends 118' of said screws are such that regardless of the positions of the parts, said ends 118' are prevented from contacting the bottoms of said openings. Engagement of the smooth lower ends 118' of screws 117 in the openings 119 of nuts 115, as stated, insures against accidental displacement of said nuts through vibration of the machine, or other causes. It will therefore appear, that when the rollers 57 and 58 have been adjusted, said rollers and their adjusting bolts will, by the locking means of the present invention, be continuously maintained in proper positions.

In accordance with the present invention, the rollers 57 and 58 may be provided with adjusting devices and locking means therefor constructed as shown in Fig. 5b, in which case the shank of the locking screw 116'' is threaded throughout its entire length so that when said screw is turned into engagement with the top of the nut 119, the latter will be canted slightly, as shown, thus binding the threads of the bolt 108 and the nut 115 and preventing turning movement of said nut until the screw 116'' is turned out of engagement therewith.

The roller 63 may be provided with adjusting and locking means such as shown in Figs. 5a or 5b. The roller 62 may also be provided with adjusting and locking means such as shown in Figs. 5a or 5b, the bearing blocks 70 for said roller, however, resting on springs 120 (Fig. 1) the opposite ends of which are received in suitable openings formed in said blocks and the bearings 69. The blocks 70 in which the trunnions of roller 62 are journaled, extend between the springs 120 and the forward ends of levers 121

which bear against said blocks. The levers 121 are pivoted, as at 122, on the sides 10 and 11 of the frame 12, and the rear ends of said levers are provided with suitable openings for the bolts 108 of adjusting devices similar to those previously described in connection with the rollers 57, 58 and 63. In the latter case, however, the bolts 108 are threaded in suitable openings in the sides 10 and 11 of frame 12, and said bolts are provided on the lower ends thereof with lock nuts 123 which bear against said sides of frame 12 and prevent turning movement of the bolts. It will appear, from the foregoing, that the roller 62 may yield relative to the roller 61 and be adjusted with respect thereto by the levers 121 and the adjusting devices connected with said levers and the sides 10 and 11 of frame 12.

The grid 59, as herein shown, is comprised by upper and lower plates 124, 125 bolted or otherwise suitably secured together in spaced relation and extending at an angle to the line of feed of sheets between the rollers 56 and 57. The grid 59 is bolted or otherwise suitably secured, as at 126, on brackets 127 which, in turn, are bolted or otherwise suitably secured, as at 128, on inclined arms or extensions 129 of the sides 10 and 11 of frame 12. The stop 60 extends in the grid 59 through longitudinal slots thereof, and said stop is adjustable along the grid, as desired, to stop the sheets at any predetermined point therein. Accordingly, the stop 60 is secured, as by a thumb screw 130 (Fig. 2) on one end of a rod 131 adjustably secured, as by a thumb screw 132, on a bracket or extension 132' on the upper end of the grid 59.

The stop 60 having been properly adjusted on the grid 59, sheets fed into said grid by the rollers 56 and 57 engage said stop so that the sheets are buckled, fed between and folded by the rollers 56 and 58. The sheets so folded may then be delivered directly out of the machine onto a stacker 133 which, under these conditions, will occupy the position thereof indicated in dotted lines in Fig. 1 of the drawings. In this case, a deflector 134 (Fig. 2) is turned to the dotted line position thereof illustrated in said figure, to deflect the sheets from the rollers 56, 58 onto the stacker 133. This deflector 134 is provided at its opposite ends with trunnions 135 (Fig. 1) rotatably and slidably received in suitable openings formed in the sides 10 and 11 of the frame 12, one of said trunnions having mounted thereon a spring (not shown) which bears against the side 10 and the adjacent end of the deflector and normally tends to urge the latter toward the side 11 of said frame. Fixed on one of the trunnions 135, exteriorly of the side 10 of frame 12 is an operating handle 136 by which the deflector may be turned to its full and dotted line positions shown in Fig. 2 of the drawings. This operating handle is provided with a pin 137 which, when the deflector is reciprocated and rotated to change its position as aforesaid, may be engaged in openings such as indicated at 137' to retain the deflector in the desired position of adjustment.

The sheets may, however, each have a second fold made therein parallel with the first fold, by the rollers 61, 63, in which case the deflector 134 is adjusted to the full line position thereof shown in Fig. 2 of the drawings. Each sheet is then guided by the deflector between the rollers 61 and 62 which feed the sheet into the grid 64 and onto driven tapes 193 that extend lengthwise of the grid and carry the sheet therealong to a point

where it is stopped by the stops 65 that have previously been adjusted to engage the leading edge of the sheet and stop it before the sheet passes out of said rollers. A folding blade 138 forming part of the folding mechanism 46 is, at this time, retained against movement by means which will hereinafter be described. When the sheet is stopped in grid 64 by the stops 65 for folding by the rollers 61, 63, said sheet is buckled, fed between, and folded by said rollers and delivered thereby across a narrow plate 139 onto the stacker 133 which, at this time, occupies the full line position thereof shown in the drawings. The plate 139 extends transversely of the frame 12 and is bolted or otherwise suitably secured to the sides 10 and 11 thereof adjacent the rollers 61 and 63.

In accordance with the present invention, the stacker 133 is mounted on the frame 12 to swing thereon to two positions in one of which the stacker may receive once folded sheets from the rollers 56, 58 and in the other of which said stacker may receive twice folded sheets from the rollers 61 and 63. The stacker 133 is preferably operated, constructed, and mounted, as follows. Fixed on the continuously rotating cam shaft 88 is an eccentric 140 around which passes a strap 141 having secured to or formed integrally therewith a short grooved arm 142 (Figs. 1, 6 and 7). Secured, as at 143, in the groove of arm 142 is a long arm 144 which is pivotally connected, as at 145, with a pawl carrier 146. This pawl carrier 146 is loosely mounted on a shaft 147 extending transversely of the frame 12 and journalled in suitable bearings on the sides 10 and 11 thereof. The carrier 146 has pivotally mounted thereon, as at 148, a pawl 149 which is adapted to engage a ratchet 150 that is fixed on the shaft 147. The arm 144 is also pivotally connected, as at 151, with one extremity of a link 152 the opposite extremity of which is pivotally connected, as at 153, with a second pawl carrier 154 that is loosely mounted on the shaft 147 between the pawl carrier 146 and the side 10 of frame 12. The carrier 154 has pivotally mounted thereon, as at 155, a weighted arm 156 which carries a pawl 157 and maintains the same in engagement with the ratchet 150.

The shaft 147 serves to drive the movable elements of the stacker 133, and is rotated intermittently in a counterclockwise direction as viewed in Figs. 1 and 6 of the drawings, through the described driving connections for said shaft with the cam shaft 88. In accordance with the present invention, the shaft 147 is rotated through a double throw action of a single eccentric or cam and connections therefor with said shaft. These connections, as herein shown, include the arm 144 and the link 152 which, during each cycle of operation of the machine, rock the carriers 146 and 154, in opposite directions toward and away from each other as indicated in full and dotted lines in Fig. 6 of the drawings. The pawls 149 and 157 are positioned reversely with respect to each other and the ratchet 150, as clearly shown in the drawings, and when arm 144 and link 152 move to the left, said pawls move in the same direction, the pawl 149 engaging one of the teeth of ratchet 150 to rotate shaft 147, and the pawl 157 sliding idly over the teeth of said ratchet. When the arm 144 moves to the right, the pawls 149 and 157 move in the same direction, the pawl 157 engaging one of the teeth of ratchet 150 to rotate shaft 147, and the pawl 149 sliding idly over the teeth of said ratchet. The

double throw action of the eccentric thus obtained acts to rotate the shaft 147 always in the same direction, and at considerably increased speed over that obtainable by the usual single throw pawl and ratchet devices.

The stacker 133 is loosely mounted on the shaft 147 to swing thereon to its different operative positions, and said shaft has fixed thereon to rotate therewith, an inner pulley 158 and outer pulleys 159 spaced from said inner pulley and arranged on said shaft at opposite sides thereof (Figs. 1, 2 and 7). Passing around the outer pulleys 159 are tapes 160 which also pass around pulleys 161 journalled in any suitable manner on brackets 162 which are bolted or otherwise suitably secured, as at 163, on a plate 164 at the rear thereof. This plate 164 has secured to or formed integrally therewith arms 165 provided therein with suitable openings through which the shaft 147 loosely extends. The tapes 160 travel over the plate 164 in the direction of the arrows (Fig. 7), the pulleys 161 and the brackets 162 extending upwardly through suitable openings formed in the rear of said plate, and the arms 165 extending forwardly and downwardly from the plate, as clearly shown in the drawings.

Passing around the pulley 158 is a tape 165a which also passes around a pulley 166 journalled in any suitable manner on a bracket 167. This bracket 167 is bolted or otherwise suitably secured, as at 168, on the forward end of a plate 169 the rear portion of which has bolted or otherwise suitably secured thereto, as at 170, brackets 171. The brackets 171 have secured to or formed integrally therewith arms 172 provided therein with slots 173 which are removably engaged over a stay shaft 174 extending transversely of the stacker and secured in any suitable manner to the arms 165 at the lower forward ends thereof. The arms 172 have rearwardly and upwardly directed extensions 175 the upper ends of which engage plate 164 on the under side thereof, as clearly shown in the drawings. The tape 165a travels over the plate 169 in the direction of the arrow (Fig. 7). The tapes 160, 165a, are intermittently driven a plurality of steps during each revolution of the eccentric 140 through the described connections therefor with the shaft 147, and said tapes serve to intermittently advance the folded sheets delivered thereon from the folding mechanism 45, over the plates 164 and 169. Curved stop fingers or the like 176 (Fig. 1) secured in any suitable manner on the plate 169 at the forward end thereof, serve to prevent accidental displacement of the folded sheets from the forward end of the stacker.

Pivoted, as at 177, on the plate 164 at the rear thereof, is a lever 178 which is adapted to be releasably engaged in one or the other of a pair of notches 179 and 180 formed in a vertically extending bar 181 that is bolted or otherwise suitably secured, as at 182, on the side 10 of the frame 12 (Figs. 1 and 7). The lever 178 has connected therewith, as at 183, one extremity of a spring 184 the opposite extremity of which is connected, as at 185, with the plate 164. The spring 184 normally tends to hold the lever forwardly in engagement with one or the other of the notches 179, 180, and by swinging said lever rearwardly against the tension of said spring, and then moving the lever vertically, the entire stacker 133 may be swung about the shaft 147 to move it to the full or dotted line positions shown in the drawings. In the full line position of the stacker shown in the drawings, the lever 178 is

engaged in the notch 179, and the stacker receives sheets from the rollers 61 and 63 of the folding mechanism 45. In the dotted line position of the stacker shown in Fig. 1 of the drawings, the lever 178 is engaged in the notch 180 of bar 181, and the stacker receives sheets from the rollers 56 and 58 of said folding mechanism.

In both positions of the stacker 133, the sheets are delivered onto the tapes 160 and plate 164, under drive-up wheels 182' which maintain the sheets in engagement with said tapes to assist the feeding action thereof (Figs. 1 and 2). These drive-up wheels 182' raise and lower in accordance with raising and lowering movement of the plate 164 which occur when the stacker 133 is swung about the shaft 147 to move said stacker to one or the other of its operative positions, as before described. Accordingly, the drive-up wheels 182' are journaled in any suitable manner on arms 183' which, in turn, are rotatably mounted on trunnions 184' formed at the opposite ends of a square shaft 185 adjustably secured, as by a thumb screw 186, on the horizontal part of an L-shaped bar 187 that is bolted or otherwise suitably secured, as at 188, on the cross bar 15. Through the provision of the thumb screw 186 and the bar 187, the drive-up wheels 182' may be adjusted longitudinally of the stacker as desired while, at the same time, said drive-up wheels are continuously maintained in engagement with the tapes 160 by gravity or weight of the wheels. The mounting of the wheels 182' and the arms 183' that carry them enable said wheels to move upwardly when sheets are fed under the same, while at the same time, the weight of the wheels engages the folded sheets with the tapes 160 to insure feeding of said sheets thereby, as before pointed out.

The folding mechanism 46, herein shown as a knife and associated folding rollers, extends at right angles to the folding mechanism 45, and the sheets, instead of being folded once or twice in parallel, and then delivered directly out of the machine onto the stacker 133, may be folded once by the first loop folder of mechanism 45 and then delivered therefrom to the mechanism 46 which makes a fold in each sheet at right angles to the fold previously made therein. In this case, the deflector 134 is shifted to the full line position thereof shown in Fig. 2 of the drawings, so that each sheet, having a single fold made therein by the rollers 56 and 58, is fed thereby across said deflector into the bite of the rollers 61 and 62 which, in turn, feed the sheet into the grid 64 toward the stops 65 which have previously been adjusted so that the sheet is entirely clear of the rollers 61, 62 before it engages said stops. In accordance with the present invention, the grid 64 has associated therewith means for feeding the sheets through the grid into engagement with the stops 65, and said means is preferably operated, mounted and constructed, as follows.

The continuously rotating spur gear 76 meshes with an idler gear 189 (Figs. 2 and 8) which is journaled in any suitable manner on the side 11 of frame 12 and meshes with a spur gear 190 that is fixed on a shaft 191 extending transversely of the frame 12 below the grid 64 and journaled in suitable bearings on the sides 10 and 11 of said frame. Fixed on the shaft 191 are rollers 192 and pulleys 192' which extend upwardly through longitudinal slots of the grid in the plane of travel of the sheets therethrough. Passing around the pulleys 192' are tapes 193 travelling in said plane and passing around pulleys 194.

The pulleys 194 also extend in the plane of travel of the sheets through the grid 64 and said pulleys are journaled in any suitable manner on brackets 195 which are bolted or otherwise suitably secured on a U-shaped plate 196. The plate 196, in turn, is positioned on the top of cross member 14 between the latter and the grid 64, and said grid and said plate are bolted or otherwise suitably secured, as at 197, to said cross member. The grid 64 comprises upper and lower plates 198 and 199 bolted or otherwise suitably secured together in spaced relation, and the end of the grid opposite that secured to the cross member 14, rests on, and is supported by, the cross member 14'. The grid 64 is provided at opposite sides thereof with scales 199' (Fig. 3a) each having two sets of graduated marks thereon whereby the stops 65 may be set for the folding of sheets of various sizes by the rollers 56, 58 or the mechanism 46 respectively.

Each sheet to be folded by the mechanism 46, passes from the rollers 61, 62 into the grid 64 over the rollers 192 and tapes 193 which act to advance the sheet in the grid until the leading edge of said sheet engages the stops 65. In order to maintain the sheet in engagement with the rollers 192 and tapes 193, and thus insure feeding of the sheet thereby along the grid to the stops 65, drive-up rollers 200 are preferably employed in conjunction with said pulleys and said tapes. These drive-up rollers 200 are journaled in any suitable manner on arms 201 which are loosely mounted on rockshaft 103 and retained against endwise displacement thereon by any suitable means for this purpose.

The stops 65 are secured to or formed integrally with holders 202 and extend into the grid between the longitudinal slots thereof (Figs. 3a and 8). The holders 202 are secured in any suitable manner on rods 203 which extend through suitable openings formed in a support 204 on which the rods are adjustably secured, as by thumb screws 205. The support 204, in turn, is adjustably secured, as by thumb screws 206, on rods 207 extending in parallel relation with the rods 203 and, in turn, secured, as at 208, on brackets 209 that are bolted or otherwise suitably fastened on the grid 64. It will appear, from the foregoing, that the stops 65 may be adjusted along the grid to any desired position, by moving the support 204 on the rods 207. A further adjustment of the stops 65 is provided through the medium of the rods 203 which may be adjusted, as desired, to move these stops longitudinally of the grid and relative to the support 204. When making these adjustments of the stops 65, the corresponding thumb screws are loosened and the stops moved to the desired position, whereupon said thumb screws are tightened to hold the stops in said position.

The knife 138 is moved, by means hereinafter described, up and down through the central longitudinal slot 138' (Fig. 3a) of the grid 64 and, in accordance with the present invention, means are provided for registering the sheet transversely of its path of travel into the grid, before the sheet is folded by said knife. As herein shown, said means comprises a manually adjustable stop 210 movable through slots 211, cut transversely of the grid at one side of the knife 138, and an automatically operated sheet registering device 212 which is movable through slots 213 cut in the grid transversely thereof at the opposite side of said knife (Figs. 3a, 4 and 8). In addition to the supporting means for grid 64, previously de-

scribed, said grid is secured by screws 214', on brackets 214 one of which carries the stop 210. These brackets 214, in turn, are bolted or otherwise suitably secured, as at 215, on the sides 10 and 11 of the frame 12. The stop 210 is secured to or formed integrally with a rod 216 provided thereon, if desired, with means for indicating various positions of the stop in accordance with various sizes of the sheets to be folded by mechanism 46. This rod 216 extends through a suitable opening in the bracket 214 on side member 11, and said rod is adjustably secured to said bracket, as by a thumb screw 217 which provides for adjustment of the rod and the stop 210 transversely of the grid 64.

The sheet registering device 212 is preferably operated, mounted, and constructed as follows. Fixed on the cam shaft 88 is a cam 218 which engages a roller 219 that is journalled on one end of a bent arm 220 (Fig. 8). This arm 220 is pivotally mounted, as at 221, on the cross member 14', and the opposite end of said arm is provided therein with an opening through which a shaft 222 loosely extends (Figs. 1, 4 and 8). This shaft 222 is rotatably and slidably mounted in a suitable opening formed in the side 10 of frame 12, and said shaft extends transversely of grid 64 and is also slidably and rotatably mounted in a suitable opening formed in a block 223. The block 223 is rigidly secured, as at 224, on one end of a guide rod 225 extending in parallel relation with the shaft 222. The opposite end of the guide rod 225 extends through a suitable opening in the side 10 of frame 12 and is rigidly secured thereto, as at 226. The arm 220 is engaged over the shaft 222 between the side 10 of frame 12 and a collar 227 which is fixed on said shaft in any suitable manner.

Exteriorly of frame 12, shaft 222 is provided thereon with a spring 228 one end of which bears against the side 10 of said frame and the opposite end of which bears against a hand wheel 229 that is fixed on the shaft and provided with a turning handle 230. The shaft 222 is provided intermediate the opposite ends thereof with a threaded portion 231 which extends through, and has threaded engagement with the walls of, an opening formed in a block 232 that carries the sheet registering device 212. This block 232 is provided at one end thereof with a slot 233 which is engaged over the guide rod 225, this engagement of the block 232 with said guide rod, preventing turning movement of the registering device 212 while enabling said device to be moved longitudinally of the shafts 225 and 222 when the latter is rotated by the hand wheel 229. The side register device 212 may thus be adjusted transversely of the grid 64 to various positions, in accordance with various sizes of sheets to be folded by the mechanism 46, or said side register device may be adjusted for removal from the path of sheets which are fed into grid 64 for folding by the rollers 61, 63.

These adjustments of the side registering device may be made independently of, but simultaneously with the operation of said device by the cam 218, the arm 220, and the spring 228, it being understood that during the operation of the machine, the sheet registering device 212 and the shaft 222 are continuously reciprocated by the cam operated arm 220 and the spring 228. It will further appear, that the spring 228 serves to maintain the roller 219 continuously in engagement with the cam 218 so that in rotation of the latter, the arm is rocked in one direction against

collar 227 to thereby move the shaft 222 in the same direction, the spring 228 thereafter acting, when the low part of cam 218 engages roller 219, to move shaft 222 and arm 220 in the opposite direction.

As each sheet fed to folding mechanisms 46 to be folded thereby, passes into grid 64 and engages stops 65, the sheet registering device 212 engages one edge of the sheet and pushes said sheet laterally of the grid so that the opposite edge of the sheet engages stop 210 and is thus registered with the knife 138 for folding thereby. The sheet registering device 212 is then moved in the opposite direction for engagement with the next sheet to register it as aforesaid with the knife 138 of folding mechanism 46. In order to prevent obstruction of movement of the sheet at the slots 211 and 213, the grid bars 234 and 235 adjacent said slots are provided with oppositely bevelled ends 236 and 237, respectively, between which each sheet is received and guided during its travel longitudinally of the grid 64 to the stops 65. In order to prevent obstruction to travel of the sheets at the slots 238 of the grid 64, the grid bars 234, 234' are provided with oppositely bevelled side edges 239, 239' and 240, 240' between which each sheet is received and guided when the side registering device 212 pushes it laterally in the grid 64 against the stop 210.

Additional sheet supporting and guiding means are provided on the grid bars 234, 234' having the bevelled edges 239', said bars being somewhat wider than the bars immediately above the same to provide increased sheet supporting and guiding surfaces. Likewise, the bars 234, 234' having the bevelled edges 240' are of greater width to provide increased sheet supporting and guiding surfaces, and said bars are of greater width than the bars provided with the bevelled edges 239'. 115

The folding mechanism 46 includes the knife 138 and a pair of knurled driven rollers 241, 242 extending in parallel relation with the knife and between which the registered sheet is tucked by said knife for folding by said rollers. The knurled rollers 241, 242 are driven in the direction of the arrows, Fig. 4 of the drawings, from the main drive shaft 24 of the machine which, for this purpose, has fixed thereon a bevel gear 243 (Fig. 2). This bevel gear 243 meshes with a similar gear 244 that is fixed on one of the trunnions 245' of a knurled roller 245 having associated therewith similar knurled rollers 246 and 247 provided at their opposite ends with trunnions 246' and 247', respectively. The rollers 245, 246 and 247 form 120 part of the folding mechanism 47 which will hereinafter be described in detail, and said rollers extend below, and in spaced parallel relation with the rollers 241 and 242 and are journalled in suitable bearings on the cross members 14, 14'. 125

Fixed on the trunnion 245' opposite that carrying the bevel gear 244, is a spur pinion 248 which meshes with a large idler gear 249 journalled on a stud 250 that is fixed on the cross member 14 in any suitable manner. This idler gear 249, in turn, meshes with a spur pinion 251 which is fixed on one of the trunnions 241' of the roller 241. The trunnions 241' of the roller 241 are journalled in fixed bearings on the cross members 14, 14'. The spur pinion 251 meshes 130 with a similar pinion 252 that is fixed on one of the trunnions 242' of the roller 242. It will appear, from the foregoing, that the rollers 241, 242 are driven continuously, in the direction of the arrows (Fig. 4) through the described driving 135

connections for said rollers with the continuously driven shaft 24. The roller 242 is yieldable relative to the roller 241 to accommodate the sheets therebetween, the roller 242 being mounted in movable bearings which are slidably mounted on the cross members 14, 14' and provided with adjusting devices and locking means therefor of the type disclosed in Fig. 5a or Fig. 5b of the drawings.

10 The knife 138 is operated from the cam shaft 18 which, for this purpose, has fixed thereon a cam 253 (Figs. 2 and 3) with which is engaged a roller 254 journalled in any suitable manner on the lower bent portion of an arm 255. This arm 15 255 is adjustably secured, as at 256, on a second arm 257 that is fixed on a rockshaft 258 extending transversely of the cross members 14, 14' and journalled in suitable bearings thereon. The rockshaft 258 also has fixed thereon a curved arm 20 259 on the free end of which is mounted the folding blade 138. The blade 138 is secured on the free end of arm 259 between the latter and a bar 260, as by machine screws 261 or the like.

25 The lower bent end of the arm 255 has pivotally connected therewith one end of a spring pressed rod 262 the opposite end of which passes through a suitable opening formed in a block 263 that is bolted or otherwise suitably secured to the cross member 14'. The spring 264 for the rod 262 is 30 mounted thereon between the block 263 and a collar 265 which is fixed on said rod in any suitable manner. The spring 264 acts to swing arms 255, 257 in one direction and the cam 263 acts to swing said arms in the opposite direction, the spring further acting to continuously maintain 35 the roller 264 in engagement with said cam. The arms 255, 257, rocking together in opposite directions as described, impart like motion to the shaft 258 which thus acts to rock the arm 259 and the blade 138 up and down so that each time 40 a sheet is delivered under and registered with the blade 138 for folding thereby, said blade descends and tucks the sheet between the rollers 241, 242 which complete the folding operation, as 45 previously described.

50 In accordance with the present invention, means are provided for preventing operation of the folding blade 138 when the grid 64 and stops 65 therein are utilized, in conjunction with the rollers 61, 62, 63, to make a second parallel fold in the sheet and deliver it directly from the machine, said means being preferably mounted, constructed, and operated as follows. The rockshaft 103 has loosely mounted thereon arms 266 55 provided in corresponding ends thereof with openings through which said rockshaft extends (Fig. 8). The opposite ends of the arms 266 are provided therein with openings for a stop rod 267 which extends transversely of the grid 60 64 under the arms 201 that carry the drive-up wheels 200. The stop rod 267 is secured against endwise displacement in the arms 266, as by machine screws 268 or the like, and endwise movement of said stop rod and said arms along the rockshaft 103 is prevented by collars 269 secured 65 to said rockshaft at opposite sides of one of said arms. Loosely mounted on the stop rod 267 between one of the arms 266 and a collar 270 fixed on said rod, is a bent lever 271 provided in the free 70 ends thereof with notches 272 and 273 one or the other of which may be engaged over a stop pin 274 secured in any suitable manner on the side 10 of frame 12 at the top thereof.

75 When the folding mechanism 46 is employed to fold sheets received from the first loop folder or

folding mechanism 45, the lever 271 is moved to engage notch 273 thereof with pin 274. The stop rod 267 is thus swung down toward the grid 64, and the arms 201 and the drive-up rollers 200 are lowered so that the latter act, in conjunction with the rollers 192 and the tapes 193, to feed each sheet longitudinally of the grid, as before described. When the grid 64, however, is employed in conjunction with mechanism 45 to make two parallel folds in each sheet, the knife 138, which otherwise would move up and down through the grid 64, is thrown out of operation and held upwardly in an inoperative position above said grid. This is effected by moving the lever 271 and engaging the notch 272 thereof with the pin 274, thus swinging the arms 266 and the stop rod 267 upwardly so that the latter engages an extension 275 of bar 260 as clearly shown in Fig. 8 of the drawings. The stop rod 267 thus acts to hold the knife 138 upwardly in an inoperative position, and prevents operation of said knife by the described operating means therefor, until the stop rod 267 is lowered by the lever 271. When the stop rod 267 is raised to throw the knife 138 out of operation, the arms 201 and the drive-up rollers 200 are likewise raised by said rod to inoperative positions. Raising of the drive-up rollers 200, as stated, is effected in order to insure against the feeding action thereof that would otherwise occur in a direction opposite to that of the feeding action of rollers 61 and 63.

100 In accordance with the present invention, an additional drive-up roller 276 is provided, which acts in conjunction with one of the tapes 193 to feed the sheets longitudinally of grid 64 for folding by the knife 138. This drive-up roller 276 is journalled in any suitable manner on an arm 277 which is loosely mounted on an adjusting screw 278 carried by a block 279. The block 279 is 105 adjustably mounted on a rod 280 and secured thereon in any desired position of adjustment, as by a screw 281. The rod 280 is pivoted at one end thereof on one of the arms 201, and the opposite end of said rod rests on the support 204 between a guide pin 282 thereon and a yoke 283 110 which is formed on said support over the knife 138 and provides for raising and lowering movements thereof. The drive-up roller 276 may, if desired, be positioned opposite the slots 213 to feed the sheets past the same, and the pivot for 115 said drive-up roller has mounted thereon a bent arm 284 which extends over the rod 280 and is engaged thereby to lift the drive-up roller 276 when the drive-up rollers 200 are lifted.

120 Each sheet folded by the knife 138 and the 130 rollers 241, 242, may be delivered directly out of the machine onto a stacker 133' which, under these conditions may occupy the full line position or the dotted line position thereof shown in Fig. 4 of the drawings, according to the positions of a 135 deflector 285 and a reversible grid and deflector 286. If, for example, the deflector 285 is positioned as shown in dotted lines in Fig. 4 of the drawings, the stacker 133' is positioned as shown in dotted lines therein. The deflector 285 is provided at its opposite ends with trunnions 287 rotatably and slidably received in suitable openings formed in the cross members 14 and 14' (Figs. 2 and 4). One of the trunnions 287 has mounted thereon a spring 288 which bears against the cross member 14 and the adjacent end of the deflector 285 and normally tends to urge the latter toward the cross member 14'. Fixed on one of the trunnions 287, exteriorly of the cross member 14, is an 140 operating handle 289 by which the deflector may 145

150

be turned to its full and dotted line positions shown in Fig. 4 of the drawings. This operating handle is provided with a pin (not shown) which, when the deflector 285 is reciprocated and rotated, may be engaged in suitable openings which are formed in the cross member 14 and serve, together with said pin, to retain the deflector in the desired position of adjustment.

The stacker 133' is constructed in substantially the same manner as the stacker 133. Accordingly, corresponding parts of the two stackers have corresponding reference characters except, that in the case of the stacker 133', the reference characters are primed. The stacker 133' is driven from the continuously rotating cam shaft 88 which, for this purpose, has fixed thereon a bevel gear 290 (Fig. 7). This bevel gear 290 meshes with a similar gear 291 that is fixed on a short shaft 292 journalled in a suitable bearing on the cross member 14' and projecting from opposite sides thereof. The shaft 292 has fixed thereon the eccentric 140' which is thus driven continuously through the described driving connections therefor with the shaft 88. The eccentric 140' serves to operate the movable parts of the stacker 133', and the shaft 147', which carries said stacker, is journalled in suitable bearings on the side 10 of frame 12. The notched bar 181' and the lever 178' serve to releasably hold the stacker 133' in either of its operative positions indicated in full and dotted lines in Fig. 4 of the drawings, and said notched bar is bolted or otherwise suitably secured to the cross members 13 and 14. Bolted or otherwise suitably secured on the plate 164' of the stacker 133', and extending transversely thereof, is a yoke 293 on the top of which is secured, as at 294, the L-shaped bar 187' (Fig. 4). Mounted on, and adjustable along the horizontal portion of the bar 187' is the square shaft 185' having trunnions at its opposite ends, as in the case of the square shaft 185. The shaft 185' is secured, as by the screw 186', on the bar 187, and the trunnions of said shaft have journalled thereon, and retained against displacement therefrom in any suitable manner, arms 295 on which are journalled drive-up wheels 296 between which and the tapes 160', the folded sheets are advanced by the latter along the stacker a plurality of steps during each revolution of the eccentric 140'. The arms 295 are provided with stops 297 which extend under the top of the yoke 293 in slightly spaced relation therewith. These stops 297 prevent undue vertical displacement of the drive-up wheels 296 while, at the same time, said stops, being slightly spaced from the top of the yoke 293, enable said wheels to raise and lower sufficiently to accommodate the folded sheets fed thereunder by the tapes 160'. It will appear, from the foregoing, that the drive-up wheels 296 are mounted on the stacker 133' and moved bodily with said stacker when the same is turned to its different operative positions about the shaft 147'. The operation of the stacker 133' is the same as the operation of the stacker 133, and when the stacker 133' and the deflector 285 are moved to their dotted line positions shown in Fig. 4 of the drawings, sheets folded by the knife 138 and the rollers 241, 242 are delivered across said deflector onto the stacker 131' between the drive-up wheels 296 and the intermittently driven tape 160'. The intermittently driven tape 160', and the intermittently driven tape 165' advance and stack the sheets along the plates 164' and 169' as will be clearly understood from the description in connection with the stacker 133.

Sheets folded by the knife folding mechanism 46 may, instead of being delivered directly out of the machine from said mechanism, be delivered therefrom to the mechanism 47 which, as herein shown, is a loop folder adapted to make a fold in the sheet parallel with the fold made therein by the preceding knife folder. The mechanism 47, as before pointed out, includes a reversible grid and deflector 286 and the feeding and folding rollers 245, 247 and 246 associated therewith. The trunnions 245' of the roller 245 are journalled in fixed bearings on the cross members 14, 14', and the trunnions 246' and 247' of the rollers 246 and 247 are journalled in movable bearings 67 slidably mounted on said cross members and yieldable to enable the rollers 246 and 247 to yield relative to the roller 245. The rollers 246 and 247 may be adjusted, as desired, with respect to the roller 245 and, accordingly, the bearings for rollers 246 and 247 are provided with adjusting devices and locking means therefor of the type disclosed in Fig. 5b of the drawings. The adjusting devices or bolts 108' for the bearings of roller 247 are somewhat longer than the adjusting devices or bolts previously described and extend outwardly through suitable slots and openings formed in the cross members 14, 14' and the side 11 of frame 12, respectively.

The rollers 246 and 247 are driven from the roller 245, and for this purpose the spur pinion 248 meshes with similar pinions 298 and 299 fixed on trunnions 246' and 247' at corresponding ends of the rollers 246 and 247. The reversible grid and deflector 286 comprises lower and upper plates 300 and 301 which are bolted or otherwise suitably secured together in spaced relation and mounted on the cross members 14, 14' so as to receive sheets from the rollers 245 and 247. For this purpose, the cross members 14, 14' have secured thereto, as by bolts 303, brackets 302 on which the reversible grid and deflector is removably secured, as by bolts 310 or other suitable fastening means. The grid plates 300, 301 have extending therein, and adjustable longitudinally thereof, a sheet stop 304 which is secured, as by a screw 305, on a bar 306. The bar 306, in turn, is adjustably secured, as by a thumb screw 307, on an extension 308 of the upper grid plate 301. This upper grid plate 301 is provided at one end thereof with a deflector 309 which, when the grid is positioned as shown in Fig. 6a of the drawings, serves to deflect sheets through the rollers 245, 247 and 246 of mechanism 47 without the sheet being folded by said mechanism.

When it is desired to fold sheets by the mechanism 47, the reversible grid and deflector 286 thereof is positioned as shown in Fig. 4 of the drawings and the deflector 285 is moved to the full line position thereof shown in said figure. The stop 304 is then adjusted properly and the sheets delivered from the rollers 241, 242, pass one after another between the rollers 245 and 247. Each sheet passing between the last named rollers is fed thereby between the grid plate 300, 301, the leading edge of the sheet engaging the stop 304 and said sheet being buckled, fed between, and folded by the rollers 245, 246. At this time, the stacker 133' is moved to the full line position thereof shown in Fig. 4 of the drawings, and the folded sheets pass from the rollers 245, 246 onto said stacker which acts to advance and stack the sheets one after another, as previously described.

It was previously pointed out, that sheets, after being folded by the mechanism 46, could be de-

- livered directly out of the machine by moving deflector 285 and the stacker 133' to the dotted line positions thereof shown in Fig. 4 of the drawings. Delivery of relatively small sheets out of the machine from mechanism 46 without further folding is, however, preferably effected by moving the deflector 285 and the stacker 133' to the full line positions thereof shown in Fig. 4 of the drawings and reversing the grid and deflector 286 from the position thereof shown in said figure, to the position of said grid and deflector shown in Fig. 6a of the drawings. In this case, the drive-up wheels 296 may, if desired, be adjusted closer to the rollers 245, 246 and the bolts 310 are removed and the reversible grid and deflector 286 is turned so that said grid and deflector occupies the position shown in Fig. 6a of the drawings where said grid and deflector is secured in said position by said bolts.
- 20 It will appear, from the foregoing, that a machine embodying the present invention is capable of making a wide variety of folds, and that the novel roller adjusting devices and locking means therefor insure against accidental displacement of the folding rollers after they have been properly adjusted. It will further appear, that the present invention enables a folding knife to be quickly and conveniently thrown into and out of operation, as desired, and that the control of the knife in this manner may be effected simultaneously with movement of drive-up rollers into and out of operative positions.
- Further, a machine constructed in accordance with the present invention enables sheets to be automatically registered laterally of the grid, as well as longitudinally thereof, and also enables sheets to be delivered directly out of the machine from different folding mechanisms onto a stacker movable into operative relation with each of said mechanisms through a simple turning movement. Further, the reversible grid and deflector of the present invention eliminates the necessity for complicated devices to permit or eliminate folding, and provides a construction which may be quickly adjusted as a single unit to cooperate with rollers in the folding of a sheet or provide for movement of the sheet through rollers without folding thereby.
- The present invention may be embodied in various types of folding machines and, while one embodiment of said invention has been described and illustrated herein with more or less particularity, it is to be expressly understood that the invention is not limited to said embodiment or otherwise than by the terms of the appended claims.
- What is claimed is:
1. In a folding machine, a loop folder, a folder having a knife movable through the grid of the loop folder, means enabling said folders to be selectively employed for folding sheets, and means for preventing operation of said knife when the sheets are folded by said loop folder.
  2. In a folding machine, a loop folder, a folder extending at right angles to the loop folder and having a knife movable through the grid thereof, means enabling said folders to be selectively employed for folding sheets, and a sheet engaging device movable to hold the knife in an inoperative position when the sheets are folded by said loop folder.
  3. In a folding machine, a loop folder, a folder having a knife movable through the grid of the loop folder, means enabling said folders to be selectively employed for folding sheets, one or
- more drive-up rollers for engaging sheets fed to the knife for folding thereby, and means movable to throw the drive-up roller or rollers out of operation and prevent movement of said knife through said grid when the sheets are folded by said loop folder. 80
4. In a folding machine, a folding knife, mechanism for operating the same, means for feeding sheets to the knife and including a sheet engaging member, and means for moving the sheet engaging member to operative and inoperative positions and including an element adapted to engage the knife and hold it in an inoperative position. 85
5. In a folding machine, a folding knife, mechanism for operating the same, a rotatable sheet engaging member, and means adapted to move said sheet engaging member to an inoperative position and prevent the operation of said knife. 90
6. In a folding machine, a folding knife, mechanism for operating the same, sheet feeding means including a roller, and a roller moving member movable into the path of travel of the knife to prevent the operation thereof. 95
7. In a folding machine, a normally reciprocating folding knife, a sheet engaging member, and means for moving the sheet engaging member to operative and inoperative positions and adapted to obstruct the movement of said knife. 100
8. In a folding machine, a normally reciprocating folding knife provided with an extension, a sheet engaging member, and means for moving said member adapted to be engaged by said extension and thereby prevent the operation of said knife. 105
9. In a folding machine, a folding knife, mechanism for operating the same, one or more drive-up rollers, and means for swinging said roller or rollers and adapted to prevent the operation of said knife. 110
10. In a folding machine, a folding knife, a drive-up roller arranged to swing to operative and inoperative positions, a pivoted member adapted to swing said roller and engage said knife, and means for swinging said member. 115
11. In a folding machine, a folding knife, mechanism for operating the same, a member movable into and out of the path of travel of the knife, and means for moving the member in one direction to prevent operation of the knife and for moving said member in the opposite direction to enable said knife to operate. 120
12. In a folding machine, a folding knife, mechanism for operating the same, a member movable into and out of the path of travel of the knife, means for moving the member in one direction to prevent operation of the knife and for moving said member in the opposite direction to enable said knife to operate, and sheet engaging means movable by said member to operative and inoperative positions. 125
13. In a folding machine, a folding knife, mechanism for operating the same, sheet engaging means movable to operative and inoperative positions, means for moving the sheet engaging means as aforesaid and adapted to prevent operation of the knife when said sheet engaging means is moved to its inoperative position, and means for locking said sheet engaging means in its operative and inoperative positions. 130
14. In a folding machine, a folding knife, a loop folder grid through which the folding knife may move when operated, and means for preventing the operation of said knife. 135
15. In a folding machine, a folding knife, a loop folder grid through which the folding knife may move when operated, and means for preventing the operation of said knife. 140
16. In a folding machine, a folding knife, a loop folder grid through which the folding knife may move when operated, and means for preventing the operation of said knife. 145
17. In a folding machine, a folding knife, a loop folder grid through which the folding knife may move when operated, and means for preventing the operation of said knife. 150

15. In a folding machine, a loop folder, a folder having a knife movable through the grid of said loop folder, and means for feeding sheets along the grid from rollers of the loop folder and comprising driven tapes extending along said grid between opposed extremities thereof. 80
16. In a folding machine, a loop folder, a folder having a knife movable through the grid of said loop folder, and means for feeding sheets along the grid for folding by said second named folder and comprising driven tapes extending longitudinally of the grid between opposed extremities thereof and rollers cooperating with the tapes and movable to operative and inoperative positions. 85
17. In a folding machine, a loop folder, a folder having a knife movable through the grid of the loop folder, means enabling sheets to be selectively folded by one or the other of said folders, driven tapes arranged to feed sheets along the grid for folding by the second named folder, rollers arranged to cooperate with the driven tapes, and means for moving the rollers to inoperative positions when the sheets are folded by said loop folder. 90
18. In a folding machine, a loop folder, driven tapes adapted to feed sheets along the grid thereof, and a folder having a knife movable through said grid and between said tapes. 95
19. In a folding machine, a loop folder including a grid, and driven tapes extending lengthwise of and adapted to feed sheets along the grid of said loop folder. 100
20. In a folding machine, folding mechanism including a grid, means for feeding sheets along the grid and including one or more drive-up rollers movable to operative and inoperative positions, and another drive-up roller movable with the first named drive-up roller or rollers to operative and inoperative positions. 105
21. In a folding machine, folding mechanism, sheet feeding means including a drive-up roller, means for moving the drive-up roller to operative and inoperative positions, a member connected with and movable by the drive-up roller, and a second drive-up roller mounted on said member and movable thereby to operative and inoperative positions. 110
22. In a folding machine, a knife folder, a loop folder having a grid on which a sheet may be fed for folding by the knife holder, and means for moving the sheet laterally of the grid to register said sheet with respect to said knife folder. 115
23. In a folding machine, a knife folder, a loop folder having a grid on which a sheet may be fed for folding by the knife folder, a sheet registering device movable transversely of the grid and adapted to push said sheet laterally thereof into register with said knife folder, and mechanism for operating said sheet registering device. 120
24. In a folding machine, a knife folder, a loop folder having a grid on which a sheet may be fed for folding by the knife folder, a sheet stop at one side of the grid, and means for moving the sheet laterally of the grid against said sheet stop to register said sheet with respect to said knife folder. 125
25. In a folding machine, a knife folder, a loop folder having a grid on which a sheet may be fed for folding by the knife folder, a sheet stop at one side of the grid and adjustable laterally thereof to various positions, and adjustable means for moving the sheet laterally of the grid against said sheet stop to register said sheet with respect to said knife folder. 130
26. In a folding machine, sheet folding means, a device for registering sheets with respect thereto, a threaded shaft carrying the sheet registering device and rotatable to adjust the same, a guide for the sheet registering device and preventing turning movement thereof on the threaded shaft, and means for moving the threaded shaft in opposite directions to operate said sheet registering device and move it along said guide. 135
27. In a folding machine, a grid slotted transversely thereof, a knife folder to which a sheet may be fed on the grid, and a device movable laterally of the grid in the slot thereof and adapted to register said sheet with respect to said knife folder. 140
28. In a folding machine, a grid slotted transversely thereof, a knife folder to which a sheet may be fed on the grid, a sheet stop adjustable laterally of the grid in the slot thereof, and means for moving the sheet laterally of the grid against said sheet stop to register said sheet with respect to said knife folder. 145
29. In a folding machine, a loop folder, a folder to which a sheet may be fed from the loop folder, and means on the grid of said loop folder for registering said sheet with respect to said second named folder. 150
30. In a folding machine, two folders having a sheet support common to both of the same, and automatically operated means on said sheet support for laterally moving and registering a sheet with respect to one of said folders. 155
31. In a folding machine, a loop folder grid in which a sheet may be fed and registered, and an automatically operated device movable in said grid to register the sheet therein as aforesaid. 160
32. In a folding machine, a loop folder grid in which a sheet may be fed, moved laterally, and stopped, means for moving the sheet laterally in the grid and operated automatically therein, and means on said grid for stopping the laterally moved sheet. 165
33. In a folding machine, a grid having a slot extending transversely thereof and grid bars with bevelled ends extending adjacent said slot to receive and guide a sheet past the same. 170
34. In a folding machine, a grid having laterally extending slots formed in different portions thereof and grid bars with bevelled ends extending adjacent said slots to receive and guide a sheet past the same. 175
35. In a folding machine, a grid having grid bars extending longitudinally thereof and provided with opposed bevelled edge portions for receiving and guiding a sheet laterally of said grid. 180
36. In a folding machine, a grid having grid bars extending longitudinally thereof and provided with opposed bevelled edge portions for receiving and guiding a sheet laterally of said grid, one of said grid bars being wider than the other to provide a supporting surface of increased size for the sheet. 185
37. In a folding machine, folding means including a roller, a roller adjusting member connected therewith, rotatable means for moving the roller adjusting member and the roller and provided with a recess, and means movable into said recess to prevent turning movement of said rotatable means. 190
38. In a folding machine, folding means including a roller, a roller adjusting member connected therewith, rotatable means mounted on the roller adjusting member and adapted, when 195

- turned, to move said member and the roller, a head on the roller adjusting member, and a device on said head movable to engage said rotatable means and prevent turning movement thereof.
- 5 39. In a folding machine, folding means including a roller, a roller adjusting member connected therewith and fixed against rotation, means for moving the roller adjusting member and the roller and comprising a nut threaded on said member and provided with a plurality of recesses, and a device movable into one of said recesses to prevent turning movement of said nut. 80
- 10 40. In a folding machine, folding means including a roller, a roller adjusting member connected therewith and fixed against rotation, means for moving the roller adjusting member and the roller and comprising a nut threaded on said member and provided with a recess, a head fixed on the roller adjusting member, and a screw 85 mounted on said head movable into said recess to prevent turning movement of said nut.
- 15 41. In a folding machine, folding means including a roller, a roller adjusting bolt connected therewith, and bolt adjusting means and locking 90 means therefor mounted on said bolt and including two members and a device for connecting said members together.
- 20 42. In a folding machine, folding means including a roller, a roller adjusting bolt connected therewith, and bolt adjusting means and locking 95 means therefor including a nut threaded on the bolt, an element mounted on said bolt coaxially with the nut, and a screw for connecting said nut and said element together.
- 25 43. In a folding machine, folding means including a roller, a roller adjusting bolt connected therewith, and bolt adjusting means and locking 100 means therefor mounted on said bolt and including two axially aligned members and a device for connecting said members together and rotatable to cant them relatively.
- 30 44. In a folding machine, folding means including a roller, a roller adjusting member connected therewith, rotatable means on the roller 105 adjusting member and acting, when turned, to move said member and the roller, and means for canting said rotatable means to prevent turning movement thereof.
- 35 45. In a folding machine, folding means including a roller, a roller adjusting member connected therewith, means for moving the roller adjusting member and the roller and including a nut threaded on said member, and means for 110 canting said nut to prevent turning movement thereof.
- 40 46. In a folding machine, folding means including a roller, a roller adjusting member connected therewith, means for moving the roller adjusting member and the roller and including a nut threaded on said member, and a screw carried by the roller adjusting member and adapted 115 to cant said nut and prevent turning movement thereof.
- 45 47. In a folding machine, folding means including a roller, a roller adjusting member connected therewith, a nut threaded on the nut adjusting member and acting, when turned, to move 120 said member and said roller, an element mounted on the roller adjusting member coaxially with the nut, and a screw adapted to connect said nut and said element and movable to cant them relatively.
- 50 48. In a folding machine, folding means including a roller, an adjusting member connected therewith, a nut threaded on the adjusting mem- 125
- ber and acting, when turned, to move said member and said roller, a head on the adjusting member, and a rotatable member adapted to connect said nut and said head together and cant them relatively.
- 55 49. In a folding machine, folding means including a roller, an adjusting member connected therewith, a nut threaded on the adjusting member and acting, when turned, to move said member and said roller, a head on the adjusting member, and a screw mounted on said head so as to connect the latter and the nut together and cant them relatively. 130
- 60 50. In a folding machine, folding means including a roller, an adjusting member connected therewith, a nut threaded on the adjusting member and acting, when turned, to move said member and said roller, a head fixed on the adjusting member, and a screw threaded through said head and adapted, when turned in one direction, to engage and cant said nut. 135
- 65 51. In a folding machine, a grid and a deflector combined as a single unit reversible to provide for use of said grid or said deflector selectively as desired. 140
- 70 52. In a folding machine, a loop folder grid and feeding and folding rollers, said grid being provided thereon with a deflector constituting therewith a single unit reversible relative to said rollers to provide for use therewith of said grid or said deflector selectively as desired. 145
- 75 53. In a folding machine, a loop folder grid provided with sheet deflecting means projecting rearwardly thereof and constituting with said grid a single unit reversible to provide for use of said grid or said means selectively as desired. 150
54. In a folding machine, a loop folder grid and a deflector constructed as a single unit reversible end for end to enable sheets to be folded by the loop folder or passed therethrough without folding thereby. 155
55. In a folding machine, a loop folder grid open at one end and provided at its opposite end with a deflector, and means for supporting and securing said grid enabling it to be reversed end for end whereby sheets may be folded by the loop folder or passed therethrough without folding thereby. 160
56. In a folding machine, a loop folder grid open at one end and provided at its opposite end with sheet deflecting means, the grid being adapted to have its open end faced toward rollers of the loop folder to receive sheets in process of folding and said grid being reversible end for end whereby said sheet deflecting means may be faced toward said rollers to deflect sheets therethrough without folding. 165
57. In a folding machine, a reversible loop folder grid open at one end and having sheet deflecting means adjacent its opposite end, the grid, when positioned with the open end thereof between rollers of the loop folder, enabling sheets to be folded by the loop folder, and said grid, when reversed, enabling the sheet deflecting means to be positioned between rollers of the loop folder so that sheets may pass through said loop folder without folding thereby. 170
58. In a folding machine, a loop folder grid open at one end and provided at its opposite end with sheet deflecting means, supporting means for the grid for holding it in position adjacent the rollers of the loop folder, and means for detachably securing the grid on said supporting means and enabling the grid to be reversed whereby its open end and the sheet deflecting 175

- means may be selectively positioned between said rollers.
59. In a folding machine, a loop folder grid provided with a deflector at the end thereof opposite that through which sheets normally enter the grid, and a support on which the grid is reversibly mounted to selectively position its opposite ends between rollers of the loop folder. 80
60. In a folding machine, a loop folder grid provided with a deflector at the end thereof opposite that through which sheets normally enter the grid, supporting means on which the grid is reversibly mounted to selectively face its opposite ends toward rollers of the loop folder, and means for detachably securing said grid on said supporting means. 85
61. In a folding machine, a grid having opposed bevelled portions faced longitudinally and laterally thereof and adapted to receive and guide a sheet moved longitudinally and laterally of said grid. 90
62. In a folding machine, a plurality of folding mechanisms, and a pivotally mounted stacker arranged to swing into operative relation with each of said folding mechanisms. 95
63. In a folding machine, a plurality of folding mechanisms, a pivotally mounted stacker, and means for swinging said stacker into operative relation with each of said folding mechanisms. 100
64. In a folding machine, a plurality of folding mechanisms, a stacker arranged to swing into operative relation with each of said folding mechanisms, and means for locking said stacker in each of its operative positions. 105
65. In a folding machine, a plurality of folding mechanisms, a stacker arranged to swing into operative relation with each of said folding mechanisms, and locking means for the stacker including a member adapted to swing said stacker into each of its operative positions. 110
66. In a folding machine, a plurality of folding mechanisms, and a stacker selectively movable into operative relation with each of said folding mechanisms by swinging movement about an axis parallel therewith. 115
67. In a folding machine, a plurality of folding mechanisms, a pivotally mounted stacker arranged to swing into operative relation with each of said folding mechanisms, and means for operating said stacker in each of its operative positions and enabling the stacker to be swung as aforesaid. 120
68. In a folding machine, a plurality of folding mechanisms, a driven shaft, a stacker mounted on the driven shaft to swing into operative relation with each of said folding mechanisms, and means connecting said shaft with movable parts of the stacker to operate the same. 125
69. In a folding machine, a stacker therefor having a section arranged to swing on the machine and a section mounted on and supported by said first named section and adapted to swing therewith. 130
70. In a folding machine, a stacker therefor having a section arranged to swing on the machine and a section removably mounted on the first named section to swing therewith. 135
71. In a folding machine, folding mechanism, stacking means adapted to receive folded sheets therefrom, operating means for the stacking means, and means connecting the operating means with the stacking means and moving said stacking means a plurality of steps during each cycle of operation of said operating means. 140
72. In a folding machine, folding mechanism, stacking means adapted to receive folded sheets therefrom, a rotatable member, and connections between the stacking means and the rotatable member and actuated thereby alternately in opposite directions to move said stacking means a plurality of steps during each revolution of said rotatable member. 145
73. In a folding machine, folding mechanism, stacking means adapted to receive folded sheets therefrom, operating means, and alternately acting multiple throw pawl and ratchet mechanism connected with the stacking means and the operating means and actuated thereby to move said stacking means a plurality of steps during each cycle of operation of said operating means. 150
74. In a folding machine, a loop folder including a grid and means for feeding a sheet therein, endless means associated with the grid for feeding the sheet therealong when said sheet is fed therein by said first named means, and means for stopping the sheet in the grid when it is fed therewith as aforesaid. 155
75. In a folding machine, a loop folder including a grid and means for feeding a sheet therein, and driven tapes extending lengthwise of the grid for feeding the sheet therealong when said sheet is fed therein by said means. 160
76. In a folding machine, a loop folder including a grid and one or more rollers for feeding a sheet therein, a stop engaged by the sheet when it travels along the grid, and driven tapes extending lengthwise of the lower part of the grid, said tapes receiving the sheet from said roller or rollers and carrying said sheet along the grid until it engages said stop. 165

CERTIFICATE OF CORRECTION.

Patent No. 1,925,269.

September 5, 1933.

JOHN MENTGES.

It is hereby certified that the above numbered patent was erroneously issued to the inventor said "Mentges" whereas said patent should have been issued to Dexter Folder Company, New York, N. Y., a corporation of New York, as assignee of the entire interest in said invention as shown by the records of assignments in this office; and that the said Letters Patent should be read with this correction therein that the same may conform to the record of the case in the Patent Office.

Signed and sealed this 28th day of November, A. D. 1933.

F. M. Hopkins

(Seal)

Acting Commissioner of Patents.
